United States Patent Office

Des. 223,864
Patented June 13, 1972

223,864

PAINT TRAY

Ellsworth Vines, Wellesley Hills, Mass., assignor to Baltimore Brushes, Inc., Boston, Mass.

Filed Mar. 10, 1971, Ser. No. 123,126

Term of patent 14 years

Int. Cl. D4—04

U.S. Cl. D64—18

FIG. 1

FIG. 5

FIG. 2

FIG. 3

FIG. 4

FIG. 1 is a perspective view from above of a paint tray embodying my new design;

FIG. 2 is a side view thereof;

FIG. 3 is a view of one end thereof;

FIG. 4 is a view of the other end thereof; and

FIG. 5 is a perspective view on a smaller scale showing the FIG. 1 tray inverted.

I claim:

The ornamental design for a paint tray, substantially as shown and described.
